DOUGLASS GRAHAM, OF WISCASSET, MAINE

DECORATIVE WALL STRUCTURE

Application filed March 24, 1930. Serial No. 438,428.

My invention relates to a decorative wall finish or decorative fabric structure which may be used as a surfacing or finish for walls. The invention may be employed as a wall finish to good advantage in many places, but in view of the fact that the present most extensive use thereof is in connection with screens and partitions I shall simplify the disclosure of the invention by confining the description and illustration thereof to the finishing of wall members of this character. As a general rule it is desired that screens shall present a pleasing and artistic appearance, and there are many uses for screens and partitions whereby one portion of a room may be segregated from another, and in some uses of screens it is desired that the surfaces thereof be waterproof, such as where a screen is to be used in a bath, or of washable character, as where the screen is used in a nursery.

My invention has in view a simple, artistic surface structure which may be used on screens or other walls. This surface structure is built up from sheets and strips of fabric, the colors of which may be selected to give artistic and pleasing combinations and balanced color effects. A fabric especially adapted to use in the practice of my invention is colored oilcloth, as such material may be obtained in many shades, is waterproof, and may be readily washed or cleaned.

An object of the invention is to provide a decorative wall surface consisting of sheets and strips of material secured to a wall structure or base in the manner to be hereinafter described.

It is an object of the invention to provide a wall surfacing structure in which strips of flexible material are applied to a base with one or more edges thereof turned under so as to form flattened half-tubes or tubes on the wall.

A further object of the invention is to provide a simple and effective method of applying a fabric tube to a wall in such a manner that the fastening means, which are generally tacks, will not be visible.

Further objects and advantages of the invention will be made evident throughout the following part of the specification.

Referring to the drawings which are for illustrative purposes only,

Fig. 1 is a perspective elevation of a simple form of screen embodying my invention.

Fig. 2 is an enlarged fragmentary elevation of one of the wall members or leaves of such a screen as shown in Fig. 1.

Fig. 3 is a cross section on a plane represented by the line 3—3 of Fig. 2.

Fig. 4 is an enlarged elevational view of a portion of a strip of fabric from which the tube element of my invention is formed.

Fig. 5 is a fragmentary elevational view similar to Fig. 2, this view illustrating the method of applying the tube element so as to cover the raw edges of the stripe members of the invention.

Fig. 6 is an enlarged fragmentary vertical cross section showing the upper edge of a wall forming part of the screen and the manner in which the edges of the surface members are covered by an edge strip.

In Fig. 1 I show a screen 10 consisting of three leaves 11 joined in the customary manner by hinges 12. Each of the leaves 11 consists of a wall including, as shown in Fig. 3, a base 13, which is conveniently made of wood, and a surface structure 14 built up of sheets and strips of fabric. The invention resides in this surface structure 14 and the simple method of applying the component parts thereof to a wall. In this simple disclosure of the invention I show a sheet of flexible material or fabric 15 which is preferably oilcloth. This sheet 15 is carried across the back 16 of the wall 13 around the edges 17 thereof and partly across the front face 18 of the wall or base 13. At the edges 20 of the sheet 15 stripe members 21 are secured, these stripe members consisting of strips of fabric, such as oilcloth, secured in the following manner: The stripe member 21 is placed in inverted position with one edge thereof lying along the edge 20 and with the remaining portion extending over the edge portion of the sheet 15 in the manner indicated by the dotted lines 22. A row of tacks 19 is then applied so as to secure the edge 20 of the sheet 15 and the edge of the stripe member 21 to the base 13. The stripe

member 21 is then applied so as to secure the edge 20 of the sheet 15 and the edge of the stripe member 21 to the base 13. The stripe

member is then swung over from the position indicated by the dotted lines 22 to the position in which it is indicated in full lines, thus causing a half-tube 23 to be formed at one edge of the stripe member 21. In this manner, one edge of the strip of material forming the stripe 21 is turned under so that the material will have a bulging or tubular effect, which condition I shall for convenience term a half-tube. When the stripe member 21 is swung over from the dotted line position 22 to its full line position, the free edge 24 thereof is laid against the face of the base 13. A second or secondary stripe member 25 is then secured in a manner substantially the same as described relative to the first or primary stripe member 21. The stripe member 25 is placed in inverted position with one edge thereof extending along the edge 24 of the primary stripe member 21 and with the remaining portion of the secondary stripe member 25 extending substantially in the direction indicated by the dotted lines 26. A row of tacks 27 is then driven to secure 25 the edge 24 of the stripe member 21 and the cooperating edge of the stripe member 25 to the base 13, after which the strip of fabric forming the stripe member 25 is swung from the position indicated by the dotted lines 26 into the full line position shown in Fig. 3, and the edge 28 of the stripe member 25 may be then secured to the base 13 by the use of tacks 30.

In the foregoing description of the application of the stripe members 21 and 25 I have confined the explanation thereof to the right-hand portion of Fig. 3, but it is to be understood that the stripe members 21 and 25 shown at the left side of Fig. 3 are applied 40 in the same manner, with the result that the flat edges 28 of the stripe members 25 extend parallel and adjacent to each other, as shown in Fig. 5. These flat edges 28 are then covered by a tube 32 which is made from a fabric, such as oilcloth, and is secured to the base 13 in a flattened form without the fastening means thereof being visible.

In the simple and preferred practice of the invention the tube 32 is made in the following 50 manner: A strip of oilcloth 33, as shown in Fig. 4, of required width to form the tube 32 has longitudinally directed tongues 34 formed in the longitudinal opposing edges 35 thereof, it being preferable to form these 55 tongues by making diagonal cuts 36 in the edges 35 substantially as shown. The opposing edges 35 are then brought into proximity to each other by rolling the strip 33 into the form of a tube. In most instances it is desirable to slightly overlap the edges 35 in the manner shown in Fig. 5. The tongues 34 are placed opposite one to the other so that when the tube 32 is formed the tongues will overlap in the manner shown at 37 and 38. When the tube 32 is placed in a centralized position

between the edges 28 of the secondary stripe member 25, it may be secured in place by means of securing means, such as tacks 40, which are driven through the overlapping tongues 34 in substantially the manner shown in Fig. 5. At 38 a pair of overlapping or co-operating tongues 34 are shown lying against the face of the base 13, while the lower portion of the tube 32 is raised or folded back but of the way to enable the driving of the tacks 40. In the securing of the strip 33, the tacking operation is advanced progressively from one pair of tongues to another until the tube 32 is secured throughout its entire length. When the tacking operation is completed, all the tacks 40 are concealed under the tube 32, and the tube is secured in its desired position without the use of complex fastening means or intricate tools, as a small hammer is the only tool necessary for securing the stripe members 21 and 25 and the tube 32 in place. I recognize, however, that other means of securing the primary and secondary stripe members and the tube 32 in place may be used, and therefore it is to be understood that my invention is not limited to the elements secured in the specific manner described but also consists in the novel compositon of sheets and strips such as those specified herein.

In Fig. 6 is shown the upper edge portion 45 of a screen member 11 having the upper edges 46 of the fabric sheets, stripes and tubes 15, 21, 25, and 32 folded over the upper face 47 of the base 13 and covered by an edge strip 48 which may be any suitable member, such as a molding strip, tape, or fabric tube, as illustrated. Securing devices in the form of nails 49 are driven down through the edge strip 48 and the overlapping upper edges 46 of the fabric members into the base 13, thereby holding the edges 46 securely and concealing them. For convenience in definition I have termed the stripe members 21 and 25 as "half-tubes", for the reason that only one edge thereof is turned under. The bulging effect obtained thereby is entirely novel, and where selected color combinations are employed for the cover sheet 15, the stripes 21 and 25, and the tube 32, very artistic and pleasing effects are produced. In the simple illustration of the invention I have shown the striping effect only on one side of each screen member, but both sides of the screen may be readily equipped with one or more systems 110 of stripes, as may be desired.

I claim as my invention:

1. In a decorative wall finish, the combination of: a base; a stripe member secured to said base; and a fabric tube secured to said base in a position covering an edge of said stripe member.

2. In a decorative wall finish, the combination of: a base; a stripe member secured to said base with one end thereof turned under

and secured to said base in a manner to form a half-tube and with the opposing edge thereof lying flat on said base; and a fabric tube secured to said base in a position covering the flat edge of said stripe member.

3. In a decorative wall finish, the combination of: a base; a stripe member secured to said base; and a flattened tube secured to said base in a position covering an edge of said stripe member.

4. In a decorative wall finish, the combination of: a base; a stripe member secured to said base with one end thereof turned under and secured to said base in a manner to form a half-tube and with the opposing edge thereof lying flat on said base; and a flattened tube secured to said base in a position covering the flat edge of said stripe member.

5. In a decorative wall finish, the combination of: a base; a stripe member secured to said base; and a fabric tube secured to said base in a position covering an edge of said stripe member, the ends of said tube being held flat so as to cause said tube to assume a flattened position.

6. In a decorative wall finish, the combination of: a base; a stripe member secured to said base with one end thereof turned under and secured to said base in a manner to form a half-tube and with the opposing edge thereof lying flat on said base; and a flattened tube secured to said base in a position covering the flat edge of said stripe member, the ends of said tube being held flat so as to cause said tube to assume a flattened position.

7. In a decorative wall finish, the combination of: a base; a stripe member secured to said base; a fabric tube secured to said base in a position covering an edge of said stripe member, said tube consisting of a strip rolled to bring its opposing edges into proximity; and means for securing said opposing edges of said tube to said base.

8. In a decorative wall finish, the combination of: a base; a stripe member secured to said base with one end thereof turned under and secured to said base in a manner to form a half-tube and with the opposing edge thereof lying flat on said base; a fabric tube secured to said base in a position covering the flat edge of said stripe member, said tube consisting of a strip rolled to bring its opposing edges into proximity; and means for securing said opposing edges of said tube to said base.

9. In a decorative wall finish, the combination of: a base; a stripe member secured to said base; a fabric tube secured to said base in a position covering an edge of said stripe member, said tube consisting of a strip rolled to bring its opposing edges into proximity, there being cuts in said opposing edges forming cooperating securing tongues; and securing means attaching said tongues to said base.

10. In a decorative wall finish, the combi-

nation of: a base; a stripe member secured to said base with one end thereof turned under and secured to said base in a manner to form a half-tube and with the opposing edge thereof lying flat on said base; a fabric tube secured to said base in a position covering the flat edge of said stripe member, said tube consisting of a strip rolled to bring its opposing edges into proximity, there being cuts in said opposing edges forming cooperating securing tongues; and securing means attaching said tongues to said base.

11. In a decorative wall finish, the combination of: a base; a stripe member secured to said base; a fabric tube secured to said base in a position covering an edge of said stripe member, said tube consisting of a strip rolled to bring its opposing edges into proximity, there being cuts in said opposing edges forming cooperating securing tongues; and securing means attaching said tongues to said base.

12. In a decorative wall finish, the combination of: a base; a stripe member secured to said base with one end thereof turned under and secured to said base in a manner to form a half-tube and with the opposing edge thereof lying flat on said base; a fabric tube secured to said base in a position covering the flat edge of said stripe member, said tube consisting of a strip rolled to bring its opposing edges into proximity, there being cuts in said opposing edges forming cooperating securing tongues; and securing means attaching said tongues to said base.

13. In a decorative wall finish the combination of: a base; a composition consisting of a plurality of stripe members secured to said base in relatively primary and secondary relationship, each stripe member having one edge thereof turned under and secured to said base so as to form a half-tube and the opposing edge thereof lying flat against said base, each relatively secondary stripe member being placed with its turned-under edge covering a flat edge of a relatively primary stripe member; and means covering the flat edge of the final relatively secondary stripe member of said composition of stripe members.

14. In a decorative wall finish, the combination of: a base; a composition consisting of a plurality of stripe members secured to said base in relatively primary and secondary relationship, each stripe member having one edge thereof turned under and secured to said base so as to form a half-tube and the opposing edge thereof lying flat against said base, each relatively secondary stripe member being placed with its turned-under edge covering a flat edge of a relatively primary stripe member; and a fabric tube covering the flat edge of the final relatively secondary stripe member.

stripe member of said composition of stripe members.

15. In a decorative wall finish, the combination of: a base; a composition consisting of

- 5 a plurality of stripe members secured to said base in relatively primary and secondary relationship, each stripe member having one edge thereof turned under and secured to said base so as to form a half-tube and the
10 opposing edge thereof lying flat against said base, each relatively secondary stripe member being placed with its turned-under edge covering a flat edge of a relatively primary stripe member; a fabric tube covering the flat
15 edge of the final relatively secondary stripe member of said composition of stripe members, said tube consisting of a strip rolled to bring its opposing edges into proximity, there being cuts in said opposing edges forming
20 cooperating securing tongues; and securing means attaching said tongues to said base.

16. In a decorative wall finish, the combination of: a base; a composition consisting

- 25 of a plurality of stripe members secured to said base in relatively primary and secondary relationship, each stripe member having one edge thereof turned under and secured to said base so as to form a half-tube and the
30 opposing edge thereof lying flat against said base, each relatively secondary stripe member being placed with its turned-under edge covering a flat edge of a relatively primary stripe member; a fabric tube covering the flat
35 edge of the final relatively secondary stripe member of said composition of stripe members, said tube consisting of a strip rolled to bring its opposing edges into proximity, there being cuts in said opposing edges
40 forming cooperating securing tongues; and nailing members passing through said tongues and securing them to said base.

17. In a decorative wall finish of the character described, a tube comprising a strip of

- 45 flexible material rolled to bring its opposing edges into proximity, said opposing edges having means adapting them for attachment to a wall member.

18. In a decorative wall finish of the character described, a tube comprising a strip of

- 50 flexible material rolled to bring its opposing edges into proximity, said opposing edges having tongues formed thereon adapting them for attachment to a wall member.

19. In a decorative wall finish of the character described, a tube comprising a strip of

- 55 flexible material rolled to bring its opposing edges into proximity, said opposing edges having cuts therein so as to form tongues

- 60 adapting them for attachment to a wall member.

In testimony whereof, I have hereunto set my hand at Los Angeles, California, this 19th day of March, 1930.

65 DOUGLASS GRAHAM.
